UNITED STATES PATENT OFFICE.

ADOLF WIDMAIER, OF ATLANTA, GEORGIA.

COMBINED TOOTHERBRUSH AND PASTE-CONTAINER.

1,385,767.

Specification of Letters Patent. Patented July 26, 1921.

Application filed February 5, 1921. Serial No. 442,811.

To all whom it may concern:

Be it known that I, ADOLF WIDMAIER, a citizen of the United States, residing at and whose post-office address is 61 Langhorne 5 street, in the city of Atlanta, county of Fulton, State of Georgia, have invented certain new and useful Improvements in Combined Toothbrushes and Paste-Containers; and I do hereby declare the following to be a full, 10 clear, and exact description of the invention, such as will enable others skilled in the art to which it appertains to make and use the same.

The invention relates to the combination 15 with a paste holding container provided with a removable cap, of a tooth brush secured to the cap, preferably by a flexible attachment, looped through a suitable hole in the tooth brush handle and secured to the 20 cap of the container to permit the latter to rotate freely, so that when the cap is in place the tooth brush is attached to the tube or container and both articles may be hung up in their appointed place by means of an 25 eye or bail connected with the cap. The particular advantages of the combination device reside in the fact that the paste container and the brush of the individual user may be kept together at all times and the cap to the 30 paste tube may not be lost or displaced, as it is always attached to the tooth brush, without interfering with the normal operation of the latter.

The invention is illustrated in the accompanying drawing, in which:—

Figure 1 is a vertical elevation of one form of the device; and

Fig. 2 is a similar view showing a modification.

Referring to Fig. 1 of the drawing, 1 indicates a standard type of collapsible tube or like container for tooth paste provided with the usual reduced screw threaded neck, through which the paste is extruded in strip 5 or ribbon form, and which neck is normally closed by an internally screw threaded cap member 2, which latter is provided with an eye 3 by means of which the tube or container may be suspended from a suitable 10 hook.

Looped about a circumferential groove or reduced portion of the cap 2 is a flexible wire bail 4, the outer end of which is passed through a hole 6 in the handle of the tooth brush 5, the end of the bail 4 being provided 15 with a hook which engages the intermediate portion of the bail and serves to lock the

looped end against accidental displacement and thereby insure the maintenance of the connection between the cap 2 and the tooth 60 brush 5, and at the same time permit the latter to be removed and connected with a new paste tube when the original one has been exhausted of its contents.

In the modification shown in Fig. 2 the 65 wire bail 4', which connects the brush with the cap 2 of the container, also constitutes the loop or eye 3', by means of which the container and the attached tooth brush is suspended from a hook or other support. In 70 other respects the device is similar to that previously described.

In each of the modifications the bail is so attached to the cap 2 as to permit the latter to rotate freely in the bail, so that the cap 75 may be readily screwed on and off the neck end of the container 1. While it is desirable that the bail be made flexible, this is not a necessary characteristic, nor is it essential that the connection between the handle of 80 the tooth brush and the bail be made detachable, for the reason that a more or less permanent form of connection may be employed, inasmuch as the same cap may be used upon different tubes or containers, provided the screw threaded neck is of the proper size to engage the interior screw threaded cap. It will also be apparent that 85 various other forms of connection between the cap and tooth brush handle may be 90 employed without departing from the characteristic features of the invention.

What I claim is:

1. The combination with a paste holder 95 having a removable cap, of a tooth brush, and connecting means looped to the handle of the tooth brush and secured to the cap to permit independent rotation of the latter.

2. The combination with a paste holder having a removable cap, of a tooth brush, and connecting means looped to the handle of the tooth brush and swiveled to said cap. 100

3. The combination with a paste holder having a removable cap provided with a suspension member, of a tooth brush, and connecting means looped to the handle of the tooth brush and swiveled to said cap. 105

4. The combination with a paste holder having a removable cap, of a tooth brush, and a flexible bail swiveled to the cap and 110 looped through the end of the tooth brush handle.

In testimony whereof I affix my signature.
ADOLF WIDMAIER.
